DESIGN FOR A JUICE EXTRACTOR

Benjamin Roseman, New York, N. Y.

Application June 9, 1945, Serial No. 119,999

Term of patent 14 years

(Cl. D89—1)

To all whom it may concern:

Be it known that I, Benjamin Roseman, a citizen of the United States of America, residing in the city of New York, county of New York, and State of New York, have invented a new, original, and ornamental Design for a Juice Extractor, of which the following is a specification, reference being had to the accompanying drawing, forming a part thereof.

I claim:

The ornamental design for a juice extractor, as shown.

BENJAMIN ROSEMAN.
